UNITED STATES PATENT OFFICE.

ROY W. FERRIS, OF MUSKEGON, MICHIGAN, ASSIGNOR OF ONE-THIRD TO WILLIAM CARPENTER AND HARRY W. JACKSON, COPARTNERS UNDER THE FIRM NAME OF CARPENTER AND JACKSON, OF MUSKEGON, MICHIGAN.

FINGERPRINT DEVICE.

Application filed December 21, 1925. Serial No. 76,868.

The general object of my present invention is the provision of a device for facilitating the making of finger prints on sheets of paper or other record material; and it 5 consists in the improvement as hereinafter described and definitely claimed.

In the accompanying drawings, forming part of this specification:—

Figure 1 is a top plan view illustrating 10 the preferred embodiment of my invention with a sheet of paper properly positioned in the device for the making of a finger print on said sheet.

Figures 2 and 3 are sections taken in the 15 planes indicated by the lines 2—2 and 3—3, respectively, of Figure 1.

Similar numerals of reference designate 20 corresponding parts in all of the views of the drawings.

I show in the drawings a sheet of paper 1 with divisions and designations appropriate to the purpose for which the sheet is intended. These divisions and designations 25 of the sheet 1 are not of the essence of my invention and it will be understood, therefore, that the sheet to be used for the reception of finger prints may be a plain sheet, may be a sheet with designations such as 30 illustrated, or may be a sheet of any other appropriate character without affecting my invention; the use of my novel device contemplating the introduction into the device 35 of sheets in succession as one criminal after another is brought up for the making of his finger print record.

Among other elements my novel device 40 comprises a body block 2, preferably of hard wood, and the device also comprises a sheet guide and retainer or holder 3. The said 45 guide and retainer is formed of thin sheet metal, in the preferred embodiment of the invention, and includes end portions 3^x attached by screws 4 to the ends of the body lock 2, spaced flanges 5 on said end portions 50 and apertured at 6 for the passage of screws or the like through the medium of which the device may be fixedly and strongly secured on a desk or other support, and a plate 7 disposed above and in spaced relation to 55 the upper side of the body block 2 and cut away as designated by 8 to leave side guiding flanges 9 with an ample space between 60 said flanges 9 for the particular portion of

the sheet of paper 1 upon which certain prints are to be made.

For the purpose of more strongly and 55 safely retaining the sheet of paper in the device and holding the sheet of paper against movement incident to the making of finger prints, the preferred embodiment of the invention comprises a bail 10, the arms of which are pivotally connected at 11 to the end portions of the block 2 and the end portions 3^x of the guide and retainer, and which retaining bail is equipped at 11^x with an 60 offset finger piece whereby it may be expeditiously and easily raised from the working 65 position shown in Figure 2.

The importance of strongly securing the 70 device on a table or other support, and the importance of strongly holding the record sheet 1 in the device during the making of finger prints will be appreciated when it is 75 stated that in many cases criminals are not amenable to the making of their finger prints, and therefore it is necessary in many cases for the officers in charge to use force in disposing the fingers of the criminal on the record sheet after the fingers have been supplied with ink in the conventional or any 80 other appropriate manner.

The sheet 1 illustrated is provided with 85 divisions designated by 13 for prints of the right thumb, right forefinger, right middle finger, right ring finger and right little finger, respectively, and these prints are 90 made after the sheet is introduced into the device in the direction indicated by arrow in Figure 1 and after the bail is swung down over the forward portion of the sheet into 95 the position shown in Figure 2 so as to strongly retain the sheet in the device and against accidental movement relative thereto. Arranged as stated the divisions 13 will be displayed between the flanges 9 of the 100 retainer and guide 3 and hence while the major portion of the hand of the criminal is supported on the major portion 7 of the guide and retainer, the desired finger or thumb print may be made in the appropriate division 13. After the making of the finger or thumb print stated, the bail is lifted and the sheet is moved in the direction indicated by arrow through the device until divisions corresponding to the division 13 and intended 105 to receive finger and thumb prints of the

other hand of the criminal are brought in coincidence with the opening between the flanges 9. Then the print of the fingers and thumb of such other hand are made, and thereupon the sheet is again adjusted through the device, still in the direction indicated by arrow in Figure 1, to position divisions or spaces 14 and 15 between the flanges 9, when with the sheet securely fastened in the device as before described, it is the province of the officer having charge of the device to secure in the division 14 the prints simultaneously of four fingers of the left hand, and to secure in the division 15 the simultaneous imprinting of the fingers, four in number, on the right hand. The identification data complementary to each of the sheets 1 used successively in the device may be filled in at the appropriate place on the sheet either precedent or subsequent to the finger printing operation as the discretion of the officer dictates.

It will be readily appreciated from the foregoing that I have provided a device for facilitating the making of finger prints that is at once simple and strong, is susceptible of ready adjustment for the manipulation of a sheet on which the prints are to be made, is adapted to strongly hold a sheet so as to lessen the liability of the same being displaced by an obstreperous criminal, and is not liable to be injured by rough handling as when it is necessary to use force in placing the finger or thumb of the criminal on the sheet.

I have specifically described the preferred embodiment of my invention in order to impart an exact understanding of all of the details of the same, the said embodiment having demonstrated in actual practice its utility and practical advantages. I do not desire, however, to be understood as confining myself to the structure and relative arrangement of the parts as disclosed, my invention being defined by my appended claims within the scope of which changes in structure and in relative arrangement may be made without departure from my invention.

Having described my invention, what I claim and desire to secure by Letters-Patent, is:—

1. A device for facilitating the making of finger prints, comprising means for supporting and providing a rest for a sheet of paper or other material, means for guiding and retaining the said sheet, and means for securing the sheet detachably against accidental movement; the said support and rest

means being in the form of a block, the said guide and retaining means being in the form of a plate spaced above the upper surface of the block and having a hand supporting portion and also having an open portion for the placing of fingers on a retained sheet, and the detachably securing means being in the form of a bail hingedly mounted and relatively arranged to clasp and bind a portion of a sheet against an opposed edge of the block.

2. A device for facilitating the making of finger prints, comprising a block, a plate spaced above the upper surface of the block and having end portions attached to the ends of the block and also having base flanges extending from said end portions and further having in its portion spaced above the upper surface of the block an imperforate hand-supporting part and an opening, and a bail hingedly connected to the ends of the block and the end portions of the plate and adapted to clasp or bind a portion of a sheet of material against the opposed end portions of the plate.

3. A device for facilitating the making of finger prints, comprising a block, a plate spaced above the upper surface of the block and having end portions attached to the ends of the block and also having base flanges extending from said end portions and further having in its portion spaced above the upper surface of the block an imperforate hand-supporting part and an opening, and a bail hingedly connected to the ends of the block and plate and adapted to clasp or bind a portion of a sheet of material against the opposed edge of the block; the said bail having at an intermediate point of its length an offset swell constituting a finger piece.

4. A device for facilitating the making of finger prints, comprising a support, a plate secured above and in spaced relation to the upper surface of the support to permit of the passage of a sheet of material between the support and the plate, said plate having a portion to support the hand and also having an opening through which the fingers may be introduced for printing purposes, and a swingable bail adapted in one position to bind or fasten a portion of a sheet against an opposed portion of the block and in another position to permit ready withdrawal of the sheet from between the support and the plate.

In testimony whereof I affix my signature.

ROY W. FERRIS.
